UNITED STATES PATENT OFFICE.

FRANK S. HERETH, OF CHICAGO, ILLINOIS.

MACHINE FOR FORMING TABLETS.

SPECIFICATION forming part of Letters Patent No. 527,980, dated October 23, 1894.

Application filed April 9, 1894. Serial No. 506,926. (No model.)

To all whom it may concern:

Be it known, that I, FRANK S. HERETH, a citizen of the United States, residing at Chicago, in the county of Cook and State of Illinois, have invented a new and useful Improvement 5 in Machines for Forming Tablets, of which the following is a specification.

My invention relates to improvements in machines for forming tablets, or the like, by compression out of more or less dry granular or pulverulent material.

The machine is intended more especially for use in making medicinal tablets, and my object is to provide an improved construction 15 which shall render the machine quick, accurate and positive in its action, readily adjustable, and particularly strong and durable.

In the drawings—Figure 1 is a broken view 20 of my improved machine partly in front elevation and partly in section, the section being on line 1 of Fig. 2; Fig. 2, a section taken on line 2 of Fig. 1, and viewed in the direction of the arrow; Fig. 3, a detail view of shake-feed mechanism; Fig. 4, a top plan view of a removable die-block holding plate; Fig. 5, a similar view of a shelf forming part of the 25 main frame; Fig. 6, a detail view of the shake-feed and discharge mechanism; and Fig. 7, a broken section on line 7 of Fig. 1.

30 A is a base, and B a frame bolted or otherwise fastened upon the base and carrying all the working parts of the machine. Journaled in bearing t t' at the top of the frame is a drive shaft C, carrying at one end fast and loose power pulleys C', and provided between the said bearings with a fly-wheel C². On the side of the frame B is a shelf or die block support B', having a smooth horizontal upper surface, and provided with a socket s, bolt 35 openings s' s', and an opening s², in the relative positions shown.

D is a removable plate which fits upon the shelf B' and has an opening r which registers with the sockets s and bolt openings r' r' which 40 register with the opening s'. In the plate D to register with the opening s² in the shelf, is an opening r², enlarged at the under side of the plate to afford an annular shoulder r³. Fitting the opening r² is a removable die-block D', provided with a central opening or die-chamber D², and an annular flange D³ at

which it fits into the enlarged part of the opening r² against the shoulder r³. When the die-block D' is inserted into the opening r² and the plate D is placed upon the shelf B', the 55 parts are secured in rigid relation by bolts passing through bolt holes r' s', and the die-chamber coincides at its center with the center of the opening s² through the shelf.

On the shaft C is an eccentric E turning in a ring E', which is provided at its lower side with a yoke E². Above and in line with the die-chamber D² is a vertically reciprocating bar or die holder E³, having a socket in its upper end to receive the lower end of a link E⁴, to which it is pivotally secured by means of a pin q. The link E⁴ has a threaded shank q', which passes through an opening q² crossing the recess q³ of the yoke E². In the yoke-recess is an adjusting nut q⁴ which engages 70 the threaded shank q', and on the shank below the yoke is a jam-nut q⁵.

The bar E³ may be raised and lowered to a limited extent, with relation to the eccentric, by turning the nut q⁴, and may be tightened 75 in adjusted position by means of the jam-nut q⁵. The bar E³ is squared between its ends where it fits and reciprocates through a squared guide opening formed by an angular groove in a projection B² on the main frame, 80 and a coincident groove in a cap-plate p bolted upon the said projection. In the lower end of the bar E³ is a socket q⁶ to receive a removable die F. When inserted in the socket q⁶ the die is secured rigidly in place 85 by means of a set screw q⁷. The lower end portion of the die fits exactly the die chamber D², and in the rotation of the eccentric the die is reciprocated into and out of the die-chamber.

90 On the shaft C is a rotary cam-block G, formed with two peripheral adjacent lying cams G' and G². G³ is a yoke provided with a longitudinally extending slot n at each side, which fits over the shaft, and a threaded 95 opening n' in its lower end to receive the threaded end of a vertically reciprocal bar G⁴, which extends through guides B³ on the main frame. Journaled in the upper end of the yoke G³ above the cam block G, is a roller 100 n² which bears against and rides upon the cam G'; and journaled in the yoke below the

cam-block G is a roller n^3 bearing against the cam G^2 . Cored through the frame B is an opening B^4 , and extending through said opening is a lever G^5 fulcrumed between its ends in the opening upon a pin m . The lever G^5 is provided at one end with an opening m' through it, at which it fits loosely over the lower end portion m^2 of the bar G^4 . The part m^2 of the bar is threaded and carries adjusting and jam-nuts m^3 above the lever, and adjusting and jam-nuts m^4 below the lever. The lever at its end m^5 is beveled at its upper and lower sides to fit loosely in and engage a socket m^6 in a vertically reciprocal bar or die-holder G^6 . The bar G^6 is squared and fits and slides in a squared guide socket formed in the face of a projection B^4 , on the main frame, and in a cap-plate p' bolted thereon. Extending through a threaded opening t^2 through the base portion of the frame B, is a set-screw H below and in line with the bar G^6 . The set-screw H is provided with a hand-wheel H' and a jam-nut H^2 . In the upper end of the bar G^6 is a socket m^7 to receive a removable die F' which is held in place in the socket by means of a set screw m^8 . The die F' fits exactly the die-chamber D^2 , and extends in at the lower end of the latter. In the rotation of the cam-block G, the cam G^2 raises the roller n^3 , yoke and bar G^4 . The lower nuts m^4 are so adjusted, with relation to the other parts, that in the rise of the bar G^4 they engage the lever G^5 and swing it on its fulcrum m to lower the bar G^6 to the set screw H. In the further rotation of the cam-block G, the cam G^2 presses the roller n^3 , yoke and bar G^4 downward, the nuts m^8 being adjusted to engage and swing the lever G^5 to raise the bar G^6 until the die F' at its upper end reaches the plane of the upper surface of the die-block D'. It is a hopper-bottomed receptacle fitting into a bracket or supporting-collar I' near the top of the machine. On the upper surface of the plate D, is a plate K, having a smooth under face; a boss l on its upper side through which extends a bolt opening l'; a bifurcated projection presenting a socket l'; a recessed and beveled edge-portion r'; and an inclined tubular projection t' through which the body-portion of the plate extends an inclined feed-passage l''. The plate K is held pivotally in place upon the plate D by means of a bolt k passing through the opening l', opening r' in the plate D, and socket s in the shelf B'. The bolt has a head k' at its upper end, and is threaded along its lower end portion to receive a nut k''. Confined between the nut k'' and under surface of the shelf is a spring k', which tends to draw down the bolt and press the plate K yieldingly upon the plate D. Extending from an opening in the lower end of the receptacle I is a flexible feed-tube I' which fits at its opposite end over the tubular projection t' of the plate K. On the end of the shaft C is a wheel K' having a seg-

mental bearing surface i concentric with the shaft, and cam-projections i' in the arc of a reduced circle.

K' is a lever pivotally mounted between its ends upon a bearing-pin p' on the cap-plate p. At its upper end the lever K' carries a roller i' to engage and ride upon the circumferential faces i' of the wheel K', and at its lower end it is reduced to fit the socket l' in the plate K. Fastened at one end to an arm B' on the frame B, and at its opposite end to the lower arm of the lever K' is a spring K'', which presses the roller i' at the upper end of the lever against the peripheral face of the wheel K'. In the rotation of the wheel K' the roller rides upon the surface i and cams i'; and turns the lever K' and through the latter the plate D on its pivot k in the horizontal plane. While the roller i' is at the surface i of the wheel the plate K is turned to one side of the die chamber D'; and when the surface i leaves the roller, the lever is actuated by its spring to spring the plate across the die-chamber and cause the feed passage l'' to register with the latter. The cams i' while passing across the roller i' give a shaking motion to the lever and plate K, whereby the mouth of the feed passage is reciprocated back and forth across the die chamber. In the upper face of the plate D is an inclined recess r', and secured to the plate at said recess is a chute L. Below the free end of the chute is a bracket or collar support L' for a pan or other receptacle L''.

In operation the pulverized or granulated material to be compressed into tablets is poured into the receptacle I. A die-block is employed having a chamber D' of the diameter of the tablets to be made, and dies F F' are employed of the proper size to fit the die chamber exactly. The set screw H is adjusted to cause the die F', when the bar G' is lowered to the set screw, to leave just the space in the die-chamber necessary to contain the exact quantity of material desired for a single tablet; and the nuts m' and m'' are adjusted to lower the bar G' to the set-screw H, when the bar G' is raised, and raise the die F' to the plane of the upper surface of the die-block and plate D, when the bar G' is lowered.

The moving parts are so constructed and timed with relation to each other, that, in the rotation of the drive-shaft, when the die F' is raised and the die F' lowered, the plate K of the shake-feed mechanism, is moved forward and shaken so that the material from the receptacle I passing through the tube I' is caused to fill the die-chamber, and the plate K is then turned backward out of the way. The bar F' is then moved to plunge the die F downward into the die-chamber and compress the material, between it and the die F', into a tablet. The force of the impact against the material and die F' is withstood by the set-screw H. Immediately following the impact, the die F is raised to the position shown in the figures, and the die F' is raised to the

top of the die-chamber and lowered again. In its rise the die F' ejects the tablet from the die chamber, and just as the said die arrives at the plane of the upper surface of the die-block the plate K is turned to strike the tablet with its edge β , and send it down the chute L to the receptacle L².

The operation of the machine is continuous and it may be operated at high speed to 10 form tablets very quickly. The shake-feed mechanism, by shaking the tube I² and the feeding and discharging plate K, agitates the tablet material and makes it flow readily through the tube and completely fill the die 15 chamber with each operation. This insures great accuracy in the size and density of the tablets, which is a matter of great importance.

By loosening the bolts which hold the plate D in place, the die-block may be quickly 20 removed and replaced with one having a die-chamber of different diameter for the formation of tablets of different size and dies of proper size to fit the die-chamber may be quickly placed in the die holders E³ G⁶.

25 The quantity of material for different tablets is regulated by adjusting the set-screw H to raise or lower the die F' in the die chamber; and the degree of compression given to the tablets may be regulated by turning the nut q⁴ to raise or lower the die-holder E³ with relation to the yoke E². As the dies fit the die chamber exactly, and necessitate great accuracy in the adjustment of the plate D and die-block, I provide the shelf B' with 30 bolt openings s' of slightly larger diameter than the coincident bolt openings r' in the plate D. This gives a slight latitude, in the matter of adjustment, desirable owing to the difficulty, which always exists in manufacture, of making such parts fit together with the exactness here necessary. The die-holders E³ G⁶ being squared and movable through squared guide openings are prevented from 35 turning on their axes, and in case of wear 40 the cap-plates may be readily tightened to prevent any lateral play of the holders.

45 My improved machine is constructed with

a view to great strength and durability, and great accuracy in the matter of adjustment, and is therefore particularly desirable for 50 the purposes for which it is more especially intended, namely, the manufacture of simple or compounded medicinal tablets.

While I prefer to construct the machine throughout as shown and described, it may 55 be modified in the matter of details of construction without departing from the spirit of my invention as defined by the claims.

What I claim as new, and desire to secure by Letters Patent, is—

1. In a tablet machine, the combination with the main-frame, drive-shaft and upper and lower reciprocal die-holders, of a die-block-support on the main-frame having a bolt-opening, a die-block on said support, a 65 feed-plate having a bolt-opening, a bolt passing through both said bolt-openings, a spring upon the bolt, operating, with the bolt, to hold the feed-plate pivotally and yieldingly upon the said support, and means connected 70 with the feed-plate and actuated from the drive-shaft, to turn and shake the feed-plate upon its pivot, substantially as and for the purpose set forth.

2. In a tablet machine, the combination 75 with the main frame and drive-shaft, and upper and lower reciprocal die holders, of a die-block support on the main-frame, a plate D removably fastened upon said support containing the die-block D' and having a bolt 80 opening r, a feed-plate K having a bolt opening l', a bolt k passing through the bolt openings r l', a spring upon the bolt, operating, with the bolt, to hold the plate K pivotally and yieldingly upon the plate D, and means 85 connected with the feed-plate, and actuated from the drive shaft, to turn and shake the feed-plate upon its pivot, substantially as and for the purpose set forth.

FRANK S. HERETH.

In presence of—

J. W. DYRENFORTH,
W. U. WILLIAMS.
